Alice White

By Thos. S. Sprague, Atty.

UNITED STATES PATENT OFFICE.

ALICE WHITE, OF DETROIT, ASSIGNOR OF ONE-HALF TO MYRON G. WOOD,
OF HILSDALE, MICHIGAN.

BUSTLE.

SPECIFICATION forming part of Letters Patent No. 406,553, dated July 9, 1889.

Application filed December 22, 1888. Serial No. 294,414. (No model.)

To all whom it may concern:

Be it known that I, ALICE WHITE, a citizen of the United States, residing at Detroit, in the county of Wayne and State of Michigan, 5 have invented certain new and useful Improvements in Bustles, of which the following is a specification, reference being had therein to the accompanying drawings.

This invention relates to new and useful 10 improvements in bustles; and the invention consists in the peculiar construction, arrangement, and combination of different parts, whereby a very light, pliable, and graceful bustle adapted to be easily adjusted is obtained, all as more fully hereinafter described, 15 and shown in the accompanying drawings, in which—

Figure 1 is a perspective view of the bustle completed. Fig. 2 is a vertical central section of my device. Fig. 3 is a rear elevation thereof, and Fig. 4 is a horizontal section on line X X in Fig. 2.

A A A' are an outer set of tubular wire coils inclosed in a fabric B, in which separate 20 vertical pockets are formed of suitable size to receive the coils by vertical seams C between the coils.

D D are an inner set of tubular wire coils of less length than the outer coils and similarly inclosed in pockets formed of an inclosing fabric E by a vertical seam F between the coils. This inner set of coils is tied to the outer set of coils by means of a bow-tape G, which connects the central portion of the 30 outer coils with its top, as shown in Fig. 2, whereby the outer set of coils are drawn into bow shape, and by passing this tape through an eyelet a in the seam F of the inner set of coils the latter are securely tied within the 35 outer set to cause the whole outer set to assume the bow shape of the central coils. The outer set of coils are united at their upper ends by being tied together by tapes b, as shown in dotted lines in Fig. 3, and to the 40 outer set to cause the whole outer set to assume the bow shape of the central coils. The outer set of coils are united at their upper ends by being tied together by tapes b, as shown in dotted lines in Fig. 3, and to the 45 two sets of coils a foundation or pad H is secured, preferably by means of the tapes c, there being one tape for each coil, so as to hold the coils and foundation in their relative position to each other. The pad is pro-

vided at its upper end with a waistband I, in 50 the usual manner.

I preferably use smaller spring-coils for the inner set than for the outer set of coils, and a less number, so as to draw the inner coils more or less into the interstices between the outer set 55 of coils; and the central coil of the outer set I make heavier than the rest. Three coils for the outer set and two coils for the inner set are generally sufficient for the purpose of forming a bustle of sufficient size; but more 60 springs may be used, if desired.

The advantage of my construction consists in its ease of adjustability and in its pliability, as it will be seen that by means of the bow-tape G, the tie-knot of which is preferably at d, so as to be easily accessible, the shape of the bustle may be altered by shortening or lengthening the tape. At the same time it will be observed that the action of the inner set of coils D modifies the shape of the 65 outer set of coils, so as to make the outer set of coils assume a more graceful shape at its upper end to form a support for the dress. At the same time all the springs are free to yield under pressure, as the expansion and contraction 70 of the spring is in no way confined, there being but one tape for the two nests of springs to unite them together and regulate the shape of the bustle. The inner set of coils by the manner of tying it into the outer set cannot 75 escape from forming a support for the bow-shaped portion of the outer set, and will always tend to maintain and restore the shape of the bustle under normal conditions, while it may be readily compressed in a vertical direction, 80 or to flatten under lateral pressure.

I deem it important that the bow-tape connect the central portion of the outer set of coils with the top of the inner set, with the bow or tie therein at the top, whereby the device is rendered easily adjustable, this construction bringing the knot at a very convenient place for adjustment, and the shape of the bustle readily altered by the lengthening or shortening of said tape.

What I claim as my invention is—

In a bustle, the combination of the outer set of coils A A A', the inclosing fabric B, in

which said outer set of coils are secured in vertical pockets formed therein, the inner set of tubular coils D D, the inclosing fabric E, forming the vertical pockets in which the said 5 inner set of coils are secured and provided with an eyelet a, the bow-tape G, adjustably connecting the central portion of the outer set of coils with the top thereof, and passing through the eyelet a of the inner set of coils, 10 the pad H, secured to the outer and inner set

of coils by the tapes c, and having the waistband I, constructed and arranged substantially as described.

In testimony whereof I affix my signature in presence of two witnesses, this 2d day of November, 1888.

ALICE WHITE.
